UNITED STATES PATENT OFFICE.

DAVID H. GRUVER, OF AUGUSTA, KANSAS; J. R. GRUVER, EXECUTOR OF SAID DAVID H. GRUVER, DECEASED, ASSIGNOR TO J. R. GRUVER, OF AUGUSTA, KANSAS.

POWER TAKE-OFF.

1,421,214.

Specification of Letters Patent. Patented June 27, 1922.

Application filed November 12, 1918. Serial No. 262,198.

To all whom it may concern:

Be it known that I, DAVID H. GRUVER, a citizen of the United States, residing at Augusta, in the county of Butler and State 5 of Kansas, have invented certain new and useful Improvements in Power Take-Offs, of which the following is a specification.

My invention relates to an improvement in power take-offs from propeller-shafts of 10 all descriptions, and it consists in a combination of mechanical elements which will be hereinafter described and pointed out in the claims.

In the accompanying drawings:—

15 Figure 1 is a longitudinal sectional view showing all of the parts assembled, except the casing which is omitted;

Figure 2 is a detached view of the intermediate shaft;

20 Figures 3 and 4 are opposite end views of the same;

Figure 5 is a side view of the hub;

Figure 6 is an end view of the latter;

25 Figure 7 is a view looking into the sliding gear;

Figure 8 is a view of the sprocket-wheel;

Figures 9 and 10 are opposite end views of the sprocket;

30 Figure 11 is a front view of the casing;

Figure 12 is a side view;

35 Figure 13 is a view of the operating lever.

F. represents a hub keyed to the drive-shaft after removing one-half of the usual universal joint, it being held the same as the 40 half of the universal joint is ordinarily held.

E, represents an intermediate shaft, the bore of which is rifled and fitted to the corresponding rifled outer surface of the hub, 45 as indicated by Figures 4 and 6. The end 1 of the intermediate shaft E is square as shown in Figure 3.

The clutch member C is slidably mounted on this square end 1 of the intermediate 45 shaft E, and the sprocket D is mounted on the cylindrical end 6 of the intermediate shaft E. A driven-shaft B has a tapered end 2 at one end, where one-half of the universal joint (not shown) goes on, and 50 the other end of this driven-shaft B has a spur gear 3. The sliding-clutch member C is confined between the driven shaft B and the sprocket D, and is provided with a female section at the left

and a male section at the right, the female 55 section having notches to receive the teeth on the spur-gear 3 when moved to the left, whereby to transmit motion to the driven shaft B, and the male section at the right is provided to engage the female section on 60 the left of the sprocket D when the clutch member C is slid to the right, whereby to transmit the power of the shaft E from driven shaft B to sprocket D.

This sliding clutch member C is shifted 65 to the right or left by a lever G which has a spanner end 4 which enters the circumferential groove 5 in said clutch member, and the lever in turn is pivoted to the transmission casing A, the moving part being 70 mounted in roller-bearings not shown to prevent friction.

I claim:

1. In a power take-off from driving shafts, the combination with a hub adapted 75 to be driven by such shaft, a driven shaft in alignment therewith, an intermediate shaft one end of which is hollowed and surrounds and has a driving connection with said hub, the other end of which intermediate 80 shaft being formed of an angular spindle, transmission means loosely mounted for rotation on the hollow end of the intermediate shaft, and a clutch member mounted on the angular spindle of the intermediate shaft, and driven thereby, but 85 slidable thereon to engage and drive either said driven shaft or said transmission means.

2. The combination with a toothed hub 90 adapted to be keyed to a drive-shaft, an intermediate shaft having a hollow cylindrical end adapted to overlie and be keyed to said hub and provided with an angular end, a sprocket-wheel loosely mounted on the cylindrical end and a sliding clutch member 95 slidably mounted on the angular end of said intermediate shaft, of a driven shaft having a spur-gear on one end, the sliding clutch member having notches to correspond with 100 said spur-teeth, and means for shifting the sliding gear into engagement with the spur gear of the driven shaft, or into engagement with the sprocket wheel whereby to transmit motion to one or the other. 105

In testimony whereof I affix my signature.

DAVID H. GRUVER.
